UNITED STATES PATENT OFFICE.

AUGUSTUS T. JONES, OF STAMFORD, CONNECTICUT, ASSIGNOR TO STAMFORD FOUNDRY COMPANY, OF SAME PLACE.

DESIGN FOR HOT-CLOSET RANGE.

Specification forming part of Design No. 7,886, dated November 24, 1874; application filed November 12, 1874.
 [Term of Patent 7 years.]

To all whom it may concern:

Be it known that I, AUGUSTUS T. JONES, of Stamford, in the county of Fairfield and State of Connecticut, have invented a Design for Hot-Closet Ranges, of which the following is a specification:

The nature of my design is fully represented in the accompanying photographic illustration, to which reference is made.

The design of portable range consists in wide and narrow rounded molding ornamentation on and near the edges of the doors of the oven and fire-chamber, said doors being also ornamented at the center with a rosette, as shown, in combination with a similar orna-

mentation of molding and rosette center on the ash-pit and warming-closet doors, and a similar ornamentation of molding at the angles formed by the four faces or sides of the range.

What I claim as my invention is—

The design for a warming-closet range, in which the doors and angles of the sides contain molding ornamentation, substantially in the manner described.

AUGUSTUS T. JONES.
